HEATING SYSTEM FOR RAILWAY CARS

Filed July 28, 1932

UNITED STATES PATENT OFFICE

1,998,808

HEATING SYSTEM FOR RAILWAY CARS

Benjamin L. Gates, Spokane, Wash., assignor of
one-half to Hannah Luella Beamish, Spokane,
Wash.

Application July 28, 1932, Serial No. 625,476

1 Claim. (Cl. 98—11)

My present invention relates to an improved heating system for railway cars which, while adapted for use in various types of railway cars and other vehicles, is especially designed for use with freight cars carrying perishable goods that require an even temperature, and also require ventilation, while in transit over the railway. In carrying out my invention I provide means actuated by the traveling car for driving a ventilating fan, and the car equipment also includes an electric motor, adapted for use in lieu of the vehicle actuated mechanism while the car is standing on a siding or in the yard, and by the alternate use of the two mechanisms the interior of the car may be ventilated as required and the temperature maintained at a uniform degree for the protection of the goods or provisions within the car.

The vehicle-actuated unit and the motor unit are provided with clutches, and a single control device, including a switch-jack is utilized for controlling the two clutches and the electric power to the motor, thereby facilitating the control of the two driving units in relation to the ventilating fan or blower.

The invention consists in certain novel combinations and arrangements of parts involving the above mentioned features as will hereinafter be more fully set forth and claimed. In the accompanying drawing I have illustrated one complete example of the physical embodiment of my invention in the equipment for a railway car, wherein the parts are combined and arranged according to the best mode I have thus far devised for the practical application of the principles of my invention, but it will be understood that changes and alterations may be made therein, within the scope of my claim, without departing from the principles of my invention.

Figure 1 is a vertical, longitudinal, sectional view of a railway freight car equipped with the system of my invention, indicating by the arrows the movement of the air currents in ventilating and conditioning the air in the car.

Figure 2 is a horizontal, longitudinal, sectional view of the enclosures and equipment, supported on the under rigging and beneath the car.

Figure 3 is a perspective view in section of the heating unit of the equipment.

Figure 4 is an enlarged, detail view, partly in section showing the control device or switch-jack for the electric power and the two clutches of the driving units of the equipment.

In order that the general arrangement and relation of parts may readily be understood I have

shown in Figure 1 a conventional freight car C with its side door D, floor F, wheels W and under rigging or frame R, and the equipment for ventilating and conditioning the interior of the car is installed beneath the car and supported on the rigging R, as indicated. 5

The heating unit includes an outer jacket 1 and an inner heating box 2 that are spaced apart to form an air space 3 which insulates the inner heating chamber within the box 2. The double 10 walled heating unit is fashioned with double doors 4 and 5, hinged at 6 in order that access may readily be had to the oil burner 7 located within the heating chamber, and the burner is supplied with oil pipe 8 from the oil tank 9, and with air 15 to support the combustion within the heating chamber.

The air from the interior of the car to be treated is drawn from its central portion through the intake pipe 10 and the intake port 11 the port, 20 as shown in Figure 1 being located flush with the floor F of the car, and the intake pipe leading therefrom to the air space 3 between the inner and outer jackets of the heating unit. From the opposite side of the heating unit an outlet pipe 25 12 leads from the air space 3 to the fan blower or impeller 13 having a central intake, and a peripheral or tangential outlet pipe 14, in order that the air may be drawn from the air space 3, through the impeller and thence passed through 30 the outlet pipe 14. Beneath the car the outlet air pipe 14 branches into two sections 15 and 16, one leading to each end of the car, and communicating with the interior of the car through ports 17 in the floor F adjacent the end walls 35 of the car.

Thus, as indicated by the lines of arrows in Figure 1 the air within the car is passed through port 11 and pipe 10 to the air space 3 and flows around the heating chamber 2 (by means of 40 which the currents of air are warmed) and thence through the fan blower or impeller 13, and the currents of heated air are distributed at opposite ends of the car. In this manner the interior of the car is continuously ventilated, and the air is 45 maintained at a predetermined temperature, which of course may be varied to suit different conditions.

As indicated in Figure 2 the fan blower is operated by belt drive 18 from the pulley 19 on the 50 countershaft 20 which is journaled transversely of the car and provided with a driven gear 23 and enclosed, with other parts of the mechanism, in a housing 24 located adjacent to the heating unit. 55

- An operating shaft, or clutch shaft 22 is also journalled in the housing, parallel with the countershaft, and this clutch shaft is provided with a gear 23 that meshes with the driven gear 21 on the countershaft. On one end of the shaft 22, exterior of the housing a pulley 25 is mounted over which passes a belt 26 and the belt is driven, as indicated by dotted lines in Figure 1 from a pulley on the axle 27 of one of the car wheels W. 5
- 10 Two friction or cone clutches 28 and 29 are mounted on the clutch shaft, and the clutch device 28 is employed to transmit power developed from the axle 27, through the driving gear 23 and driven gear 21, to operate the fan blower while the 15 railway car is traveling.

While the car is standing on a siding or in a railway yard, the clutch 28 is rendered inoperative, and the clutch 29 is employed to transmit power to the fan blower, which power is imparted to and through the clutch from the belt drive 30 and 31 of the electric motor 32, the latter also being enclosed in the housing 24.

The two clutches are simultaneously shifted, one into operation and the other out of operation, by the utilization of a single clutch lever 33, which is pivotally supported within the housing and connected in suitable manner with the clutch devices. Within the housing a lever rod 34 is pivotally connected to one end of the clutch lever, 25 and this rod is slidable, transversely of the car in suitable bearings. One end of the slide rod is fashioned with a head 35, that is enclosed within a housing 36, and the rod is slidable in one of the walls of this housing as indicated in Figure 4. 30 Between the wall of the housing 36 and the head 35 a spring 37 is interposed and coiled about the rod 34, and this spring is adapted to slide the rod 34 and swing the clutch lever 33 in such manner as to disengage the clutch 29 of the electric 35 motor and engage the clutch 28 of the vehicle-actuated driving mechanism. Thus, by use of the spring, the clutch of the electric drive is normally held inoperative, while the clutch of the vehicle-actuated drive for the fan blower is held 40 in operation.

For controlling the two clutches and the supply of electric current to the motor I employ a portable switch jack having a handle 38 and plug 39, the latter being provided with spring 45 blades 40 and terminals 41 for the wires 45 that may be attached by suitable means to a source of

power, or electric current, and which pass through the hollow handle of the switch jack to the terminals.

The jack is "plugged" into a socket plug 42 which is secured in a hole in the wall of the housing 24 and provided with an attaching flange 43, screws, bolts, or other fastening devices being used to secure the socket-plug to the wall of the housing.

Within the socket-plug are provided contact terminals 44 to which the wires 45 are connected, and of course the stationary terminals or contacts 44 are in position to receive contact from the spring blades 40 of the switch jack. The wires 45, as indicated in Figure 2 extend to the electric 15 motor, and it will be apparent that the motor circuit is closed for the operation of the motor, when the jack is "plugged" in to the socket plug.

The plugging action of the jack also controls the two clutches 28 and 29, clutch 28 being disengaged and clutch 29 engaged, when the jack is inserted in the socket plug. For this purpose I employ a slide bolt 46 which is slidably supported in the socket-plug and in a hole in the housing 36, and the bolt is alined with the longitudinal axis of the jack. Thus, by the action of plugging in or pushing the jack into its socket plug, the bolt, which is in contact with the adjoining end of head 35 of the rod 34, pushes the rod to swing the clutch lever for controlling the clutches. The 30 jack and the socket-plug are provided with a lock in the form of a pin 47 and a bayonet slot 48, thereby permitting the jack to be turned slightly after insertion in the socket-plug, to lock the clutch device.

Having thus fully described my invention, what I claim as new and desire to secure by Letters Patent is:—

In a ventilating system for railway cars including an air-heater, an air impeller and air 40 pipes connecting said heater and impeller with the interior of the car, of a vehicle-actuated mechanism including a clutch, an electric motor and its driving mechanism including a clutch for the driving mechanism, transmission mechanism 45 between said mechanisms and the impeller, an electric control switch for said motor operating means for said switch, and means actuated by said operating means for alternately rendering active said clutches.

BENJAMIN L. GATES.
